UNITED STATES PATENT OFFICE.

EDGAR E. PHINNEY, OF NEW YORK, N. Y., ASSIGNOR TO MONROE CALCULATING MACHINE COMPANY, OF NEW YORK, N. Y., A CORPORATION OF NEW YORK.

CALCULATING-MACHINE.

1,330,651.

Specification of Letters Patent.

Patented Feb. 10, 1920.

Application filed January 13, 1917. Serial No. 142,190.

To all whom it may concern:

Be it known that I, EDGAR E. PHINNEY, a citizen of the United States, resident of New York, in the county of New York and 5 State of New York, have made a certain new and useful Invention in Calculating Machines; and I declare the following to be a full, clear, and exact description of the same, such as will enable others skilled in 10 the art to which it appertains to make and use the invention, reference being had to the accompanying drawings, and to letters or figures of reference marked thereon, which form a part of this specification.

15 Figure 1 is a side view of the machine, with the casing broken away.

Fig. 2 is a similar view with a character key depressed, the carrier frame for the selecting elements raised, the operating or 20 double cranked shaft turned one quarter around, and a selecting element thrown from starting position (shown in Fig. 1) to the limit of movement in one direction.

Fig. 3 is a plan view of one half of the 25 machine with parts broken away.

Fig. 4 is a section on the line 4—4, Fig. 3.

Fig. 5 is a detail side view of the carrier frame for the selecting elements, showing said elements, the carrying shaft, and parts 30 carried thereby.

Fig. 6 is a section on the line 6—6, Fig. 2, partly broken away.

Fig. 7 is a section on the line 7—7, Fig. 6.

Fig. 8 is a similar view with the over- 35 throw check engaged with the intermediate gear.

Fig. 9 is a detail side view of one of the collars upon the carrying shaft.

Fig. 10 is a similar view of another collar 40 adjacent to the collar of Fig. 9, the pin of one collar being opposite the slot of the other collar.

Fig. 11 is a section on the line 11—11, Fig. 10.

45 Fig. 12 is a detail side view of a carrying dog and spring.

The invention has relation to calculating machines for performing problems in addition, subtraction, multiplication and division, and registering the results, an object being to provide a machine having a plurality of series or banks of denominational keys and wherein a single operating device

or crank handle is used in the registration, said handle having the same starting and 55 stopping point for the various problems and being operable either forwardly or backwardly, or in two directions, according to the nature of the problem, and the machine embodying selecting or differential 60 actuating elements or the general rack type, said elements having always the same length of stroke. A further object is to provide selecting elements capable of being axially 65 turned to bring more or less teeth thereof into play. Other objects and advantages will hereinafter appear.

The invention consists in the novel construction and combinations of parts, as hereinafter set forth.

In the accompanying drawings, illustrating the invention, the numeral 2 designates the casing; 3 the numeral keys, arranged in a plurality of denominational series each from 0 to 9 inclusive; 4 a rear transversely 70 shiftable carriage, pivoted to the casing at 4'; 5 a series of registering wheels upon shaft 6, said shaft having bearings in said carriage; 7 a second series of registering 75 wheels, upon the same shaft 6; 8 a series of 80 carrying dogs or pawls upon shaft 9; 10 a series of selecting or differential actuating elements, one selecting element for each series of numeral keys, said elements being rotatably fast and slidable upon shafts 10'; 85 11 a series of intermediate gear wheels upon shaft 12, said gears operating the registering wheels and being actuated by the selecting elements and also by the carrying dogs; and 13 is an operating device or crank handle upon shaft 14, said handle operating the 90 selecting elements and the carrying mechanism.

15 is a series of longitudinal levers, pivoted or fulcrumed respectively at their rear 95 ends at 16 and engaged by shoulders 17 of the numeral key stems 17', there being one lever for each denominational series of keys, the different key stems of the same denominational series being spaced from the fulcrum of the corresponding lever by varying distances, to accomplish a greater or less depression of the lever, according to the value of the key depressed. The key stems in any denominational series are 100 held down by a spring-pressed bar 19,

common to the series and pivoted at 20, said bar engaging shoulders 21' of the key stems for this purpose, and the levers 15 being held down by the depressed keys.

5 The levers 15 have respectively engagement with vertical racks 40, engaging pinions 41 of the shafts of the selecting elements, to cause, in the depression of said levers, an axial rotation of said elements, 10 each element being turned more or less, according to the value of the key depressed, as previously explained.

The shafts 10' of the selecting elements are mounted in a frame 21, pivoted forwardly at 22 and adjustably supported in rear by shafts 23, said shaft carrying a cam 24, whereon bear at opposite points rollers 25 of said frame, whereby, for each rotation of said shaft, the frame is raised from 20 normal depressed position, raising the shafts 10' and the selecting elements into position to rotate the intermediate gears 11, upon sliding movement of said elements upon their shafts, the frame and the selecting elements being normally in lowered 25 position, for reasons stated hereinafter.

The shaft of the operating handle is provided with a bevel gear connection 26 with a longitudinal shaft 27, said shaft having 30 bearings in the casing or base and being provided with a double cranked portion 28, including an inclined part 29, a transversely extending arm 30 at one end thereof loosely engaging said inclined part and at its opposite end engaging a reciprocating slide frame 31, by means of a universal joint 30', the frame having rollers 32, working in guides 33 of the casing whereby upon operation of the shaft 27, brought about by a 35 half turn of the crank handle, the inclined part 29 of said shaft is caused to assume an opposite inclination and to move said arm and the slide frame rearwardly or forwardly, as the case may be, and thereby, 40 owing to the engagement of the endmost teeth of the selecting elements with slots 34 of a transverse extension 35 of said frame, to move all of the selecting elements longitudinally upon their shafts.

45 The selecting elements are each provided with nine teeth, starting all from the same radial position relative to the element and being continued around the element to varying degrees, gradually increasing from one end to the other, a longitudinal blank or untoothed space 70 being left between all of the teeth of each element, so that, in the sliding movement of the elements, those not previously axially turned by operation of 55 the numeral keys will have no action upon the corresponding intermediate gears.

The shaft 27 has at its rear end bevel gear connections 36 with a transverse shaft 23, the latter shaft having spur gear connection 38 with the carrying shaft 9, and turn-

ing the carrying shaft four times around for each turn of the crank handle.

In performing addition and multiplication, the operating handle is turned clockwise once completely, to thereby move the frame 21 and to move the selecting elements longitudinally upon their shafts, from normal lowered position, midway of the lengths of their strokes, to raised position, at the forward end of the strokes, then rearwardly to 75 the opposite end of the strokes, and then to return said elements to normal position, the carrying being performed while the elements are so returned, in the same clockwise movement of the handle; and in performing subtraction and division, the handle is turned counter-clockwise once completely, to move 80 said frame and to move the selecting elements from normal position to raised position, at the rear end of their strokes, then forwardly to the opposite end of the strokes, and then to return the elements to normal position, the carrying being performed as 85 stated, while the elements are so returned.

In order that said elements shall be returnable backwardly or forwardly, as the case may be, without actuation of the intermediate gears by those elements that have been axially turned, it is necessary that, after the elements have been moved longitudinally, as 95 stated, they shall be lowered and then returned, so lowered, to normal position. And inasmuch as the selecting elements are movable either rearwardly or forwardly, according to the nature of the problem, and as the 100 carrying is performed after the elements are so moved, it is necessary that they shall normally be located in lowered position, midway of the ends of their strokes.

The numeral keys are first depressed as 105 required for the particular problem, the levers 15 being at the same time depressed to varying degrees, as stated, and the selecting elements turned axially also to varying degrees. The operating handle being now 110 turned, during the first quarter turn the selecting elements are moved longitudinally, from normal lowered midway position, to position at one end or the other of the strokes thereof and raised to effective starting 115 position; during the next half turn of the operating handle the selecting elements are moved longitudinally, all having the same length of stroke and engaging and turning the registering wheels to varying degrees, according to the values to which said elements are set; and during the last quarter stroke of said handle the carrying 120 operation is performed.

The shafts 10' and the selecting elements 125 thereon are turned axially back to normal position by springs 11² (Fig. 3).

The carrying shaft 9 is provided with a series of annular collars 42, each collar having guides 43 wherein works a transversely 130

slidable dog or tooth 8, and having also a transversely extending pin 45, working in a slot 46 of the collar next adjacent thereto at one side, the collar 42^a at one end of the 5 series being fast to the shaft and all of the other collars having usually a frictional bind upon the shaft, to rotate therewith, but admitting of a movement of the collars with respect to the shaft against such frictional 10 bind or resistance. The fast end collar and all of the other collars have each a pin and slot, as stated. The dogs of all of the collars are arranged spirally, entirely around the shaft in a single series.

15 In the reverse or counter clockwise movement of the shaft, to rearrange the teeth or dogs of the collars to reverse spiral, the fast end collar 42^a, all of the other collars 42 and the other end collar 42^b will turn with the 20 shaft, the pin 45^a being held temporarily from turning with the shaft, by suitable means. Therefore, this pin 45^a will next arrive at the end of the slot 46 of the collar 42^b, and will then check said collar 42^b from 25 further movement with the shaft, said collar having moved a distance equal to the length of the slot 46.

The pin 45 of the collar 42^b being now checked with said collar from further rotation with the shaft, the second collar 42 in line will move with the shaft the length of the slot 46 thereof, when the end wall of said slot will be brought against the pin 45 of collar 42^b, to prevent further movement with the shaft of said second collar in line, said collar having moved with the shaft a distance equal to the combined length of two slots 46. This step by step or successive checking of the collars will follow in the reverse movement of the shaft throughout the line of collars, to the fast collar 42^a, which will, when the spiral rearrangement is completed, have moved a distance equal to the sum of the length of all of the slots 46, the collar next adjacent thereto 45 a distance equal to the sum of the length of all of the slots less the length of one slot, etc.

The collar 42^a is made fast to the shaft 50 by a pin *s* thereof engaging a radial notch *s'* of an extra collar *t*, fast to the shaft.

In the clockwise movement of the operating handle, the same action takes place to check the movement of the pin 45^a with the shaft 9 while rearrangement of the carrying teeth to reverse spiral is being accomplished.

Located between the intermediate gears 11 are reciprocatory carrying members 47, pivoted at 48 and having each an arm 49, 60 normally extending in the path of a transverse pin 50 of a registering wheel 5, each registering wheel having a pin 50, and said member having an oppositely projecting arm 51, provided with a cam surface 52, 65 adapted to extend within the path of move-

ment of a carrying dog, there being one member 47 for each dog and for each registering wheel.

The cams 52 of the arms 51 are each double, having two inclined cam surfaces, 70 one of which acts upon the dogs to move them endwise in the rotation of the carrying shaft clockwise, and the other oppositely inclined part acting to move the dog endwise in the reverse spiral arrangement, the dogs 75 moving endwise in the same direction into active position in each case. The dogs are returned to normal position by springs 53 thereof (Fig. 12) and the pivoted carrying members are returned to normal position by 80 radial projections or fingers 54 of the carrying shaft, said fingers following the dogs and having end cam surfaces 55, engaging said members, the cams 55 being double, having oppositely inclined parts, to return said 85 members in either direction of rotation.

The radial fingers 54 are loosely mounted upon the carrying shaft, between the collars thereof, each finger having a connection with the end of a pin 45 of the second collar 90 therefrom at one side thereof, and being movable with said pin and collar, in the rearrangement to reverse spiral of the carrying dogs, to position at the opposite side of the carrying dog of the adjacent collar at 95 this side. The fingers, being moved to the opposite sides of the carrying dogs, are in position to return the carrying members 47 to normal position after said members have acted upon said dogs upon reverse movement of the carrying shaft.

Located between the intermediate gears are collars 56, carrying each a spring-pressed pin 57, said pin engaging either of 105 two recesses 58 of the pivoted carrying members, to retain them in normal position and in position when thrown pivotally.

In order that, during the rotation of the registering wheels in setting up the problem, the carrying dogs shall not be moved 110 endwise into effective position by those of the carrying members 47 that have been pivotally thrown by the transverse pins of the registering wheels, and shall not, in the turning of the carrying shaft, engage and 115 turn the registering wheels, it is provided that the carrying shaft shall be movable toward and away from the registering wheels, the dogs upon said shaft being movable therewith into position for engagement with 120 said carrying members, said dogs being thereby slid into active position and rotating the registering wheels upon the last portion only of the turn of the crank handle. For this purpose, the carrying shaft is 125 mounted at the outer end of one arm of bell crank levers 59, fulcrumed upon the shaft 23, the outer end of the other arms of said levers having pivotal connection with the frame 21 at 60, whereby, as the frame is 130

raised from normal lowered position, the lever is rocked, to rock the carrying shaft and its dogs away from the registering wheels, and as the said frame is lowered, after the registering wheels have been rotated in setting up the problem, the carrying shaft and its dogs are rocked toward the registering wheels.

In setting up the first item and registering the same, certain of the numeral keys being depressed, for instance keys 9, 9, 9, in the first three series, representing units, tens and hundredths, the corresponding selecting elements will be axially turned, and the operating handle being then rotated, the three corresponding intermediate gears will be rotated, and thereby the three corresponding registering wheels will be turned to register the number.

In addition, the next item being set up by depressing certain of the numeral keys, as those previously referred to, to add 999, the selecting elements will be turned axially, and the operating handle being rotated, said elements will be thrown longitudinally to rotate the units, tens and hundredths registering wheels nine teeth again, the transverse pins of the units tens, and hundredths registering wheels engaging the corresponding pivoted carrying members and throwing said members pivotally to bring the cams 52 of the arms 51 thereof into the path of the corresponding carrying dogs, said dogs, in the rotation of the carrying shaft, being thereby slid endwise or transversely of the machine, into position to, upon further turning of the carrying shaft, engage the teeth of the gears 11 corresponding to the tens and hundredths registering wheels and turn the same one tooth additionally, and engage the teeth of the gears 11 corresponding to the thousandths registering wheel and turn the same one tooth.

Means are provided to retain the shafts of the selecting elements in position as axially turned, with the elements thereupon, in setting up the problem, consisting preferably of a transverse bar 62 at the rear of the machine, said bar having depending fingers or teeth 63, said teeth individually engaging with the teeth of ten-tooth gears 64, mounted upon the rear ends of the shafts of the said elements, said gears being raised with the frame 21 to engage said teeth, and depressed with said frame to disengage from said teeth.

Means are provided to indicate the number set up by axial turning of the selecting element corresponding to each denominational series of keys, consisting preferably of a crown gear 65 upon each of the shafts of the selecting elements, said gear engaging a pinion 66 of an upright staff 67, said staff carrying at its upper end a dial 68, bearing a series of numerals from 0 to 9 inclusive

and registering with a sight opening 69 of the top plate of the casing.

Upon the shaft 6 of the registering wheels 5 is located a second series of registering wheels 7, sight openings in the carriage exposing the number upon the latter wheels indicating the quotient in division and the multiplier in multiplication, as also the number of items in addition. The wheels 7 are operated individually from the shaft 27, each rotation of the operating handle rotating the wheel 7 to be operated, one tooth, this being accomplished by means of a pawl 71, the upper end of which is adapted to engage the gear 7' of the wheel 7 to be turned, and the lower end of which loosely engages a slot 72 of a stationary frame piece 73, the intermediate portion of said pawl having a lateral pin 74 engaging eccentrically a disk 75 upon shaft 76, said shaft having crown gear 77 in mesh with a spur gear 78 upon shaft 27.

The levers 15 are provided with upper and lower stop projections 160, 161, (Fig. 1) engaging respectively the upper and lower keyboard plates of the casing.

I claim:—

1. In a calculating machine, registering wheels, gears in connection therewith, selecting elements having each a plurality of circumferential teeth of graded lengths, said elements rotatable selectively to set up a varying number of the teeth thereof and longitudinally movable to an equal degree in meshing relation with said gears.

2. In a calculating machine, registering wheels, gears in connection therewith, selecting elements having each a plurality of circumferential teeth of graded lengths and a longitudinal space between the ends of the teeth, said elements rotatable to set up a selected number of the teeth thereof and longitudinally movable in meshing relation with said gears.

3. In a calculating machine, registering wheels and axially movable selecting elements, each element having circumferential teeth of graded lengths and being longitudinally movable in two directions to turn said registering wheels in either direction of movement, and means for moving said elements into and out of operative position with relation to said registering wheels upon the effective and upon the return strokes thereof.

4. In a calculating machine, registering wheels, rotatable shafts, selecting elements rotatably fast and longitudinally slidable upon said shafts, each element having circumferential teeth of graded lengths, a carrier for said shafts movable upwardly and downwardly, and means for raising and lowering said carrier and for moving said elements longitudinally.

5. In a calculating machine, registering

wheels, gears in connection therewith, selecting elements, each element having circumferential teeth of graded lengths, means for turning said elements axially, and means for moving the elements longitudinally in meshing relation with said gears.

6. In a calculating machine, registering wheels, gears in connection therewith, selecting elements, each element having circumferential teeth of graded lengths, a plurality of denominational series of keys adapted to turn said elements axially, and an operating device for moving the elements longitudinally in meshing relation with said gears.

15 7. In a calculating machine, registering wheels, rotatable shafts, selecting elements rotatably fast and longitudinally slidable upon said shafts, said elements having each circumferential teeth of graded lengths, a carrier for said shafts movable upwardly and downwardly, a plurality of denominational series of keys adapted to turn said shafts axially, and an operating device adapted to raise and lower said carrier and 25 to move said elements longitudinally to turn the registering wheels.

8. In a calculating machine, registering wheels, gears in connection therewith, selecting elements, each element having circumferential teeth of graded lengths, depressible keys for turning said elements axially, and a rotary operating device for moving said elements longitudinally in meshing relation with said gears.

35 9. In a calculating machine, registering wheels, gears in connection therewith, selecting elements, each element having circumferential teeth of graded lengths, and being longitudinally movable in two directions to turn said registering wheels in either direction of movement, depressible keys adapted to turn said elements axially, and a rotary operating device rotatable in two directions to move said elements longitudinally in meshing relation with said gears in either direction of rotation.

10. In a calculating machine, registering wheels, gears in connection therewith, selecting elements, each element having circumferential teeth of graded lengths, depressible keys for turning said elements axially, and a rotary operating device for raising and lowering said elements into and out of meshing relation with said gears and 55 for moving the same longitudinally in two directions to turn the registering wheels and to return said elements to normal position.

11. In a calculating machine, registering wheels, rotatable shafts, selecting elements 60 rotatably fast and longitudinally slidable upon said shafts, each element having circumferential teeth of graded lengths, a carrier for said shafts movable upwardly and downwardly, depressible keys adapted 65 to turn said shafts axially, and means for

moving said carrier upwardly and downwardly and said elements longitudinally including a rotary handle, a cranked shaft, and an arm engaging the cranked portion of said shaft.

12. In a calculating machine, registering wheels, rotatable shafts, selecting elements rotatably fast and longitudinally slidable upon said shafts, each element having circumferential teeth of graded lengths, a carrier for said shafts movable upwardly and downwardly, depressible keys adapted to turn said shafts axially, and means for moving said carrier upwardly and downwardly and said elements longitudinally including a rotary handle, a shaft having a double crank including an inclined part, a slide, and an arm loosely engaging said inclined part and pivotally engaging said slide.

13. In a calculating machine, registering wheels, rotatable shafts, selecting elements rotatably fast and longitudinally slidable in two directions upon said shafts, each element having circumferential teeth of graded lengths, a carrier for said shafts movable upwardly and downwardly, depressible keys adapted to turn said shafts axially, and means for moving said carrier upwardly and downwardly and said elements longitudinally including a rotary handle rotatable in two directions, a shaft having a double crank including an inclined part, a slide, and an arm loosely engaging said inclined part and having a universal joint connection with said slide.

14. In a calculating machine, registering wheels, rotatable shafts, selecting elements rotatably fast and longitudinally slidable in two directions upon said shafts, each element having circumferential teeth of graded lengths, a pivoted carrier for said shafts movable upwardly and downwardly, depressible keys adapted to turn said shafts axially, and means for moving said carrier upwardly and downwardly and said elements longitudinally including a handle rotatable in two directions, a longitudinal shaft having a double crank including an inclined part, a transverse shaft having cam engagement with said carrier, a slide member engaging said selecting elements, and an arm loosely engaging said inclined part and having a universal joint connection with said slide member.

15. In a calculating machine, registering wheels, gears in connection therewith, selecting elements, each element having circumferential teeth of graded lengths, means for turning said elements axially, means for moving the elements longitudinally in meshing relation with said gears, and means for retaining the elements in position as axially turned during the turning of said wheels.

16. In a calculating machine, registering wheels, rotatable shafts, selecting elements rotatably fast and slideable longitudinally upon said shafts, said elements each having 5 circumferential teeth of graded lengths, a carrier for said shafts movable upwardly and downwardly, depressible keys for turning said elements axially, an operating device adapted to raise and lower said carrier 10 and to move said elements longitudinally to turn the registering wheels, and fixed means coöperating with said shafts to retain said elements in axially turned position during the turning of said wheels.
- 15 17. In a calculating machine, registering wheels, rotatable shafts, selecting elements rotatably fast and slideable longitudinally upon said shafts, said elements each having circumferential teeth of graded lengths, a 20 carrier for said shafts movable upwardly and downwardly, depressible keys for turning said elements axially, an operating device adapted to raise and lower said carrier and to move said elements longitudinally 25 to turn the registering wheels, said shafts having ten toothed wheels, fingers engaging said wheels upon the upward movement of said carrier to retain said elements in axially turned position.
- 30 18. In a calculating machine, registering wheels, rotatable shafts, selecting elements rotatably fast and longitudinally slideable upon said shafts, each element having circumferential teeth of graded lengths, a carrier for said shafts movable upwardly and downwardly, depressible keys adapted to turn said shafts axially, means for raising and lowering said carrier and for moving said elements longitudinally to turn the registering 35 wheels and reversely to normal position including a rotary handle, and fixed means coöperating with said shafts to retain said elements in axially turned position during the actuation of the registering 40 wheels.
- 45 19. In a calculating machine, registering wheels, rotatable shafts, selecting elements rotatably fast and longitudinally slideable upon said shafts, each element having circumferential teeth of graded lengths, a carrier for said shafts movable upwardly and downwardly, depressible keys adapted to turn said shafts axially, carrying mechanism including a rotary shaft bearing carrying members, means for moving said carrier upwardly and downwardly and said elements longitudinally to turn the registering wheels, and for rotating the carrying shaft including a rotary handle, and means co- 50 operating with said carrier for moving said shaft bodily toward and away from said wheels.
- 55 20. In a calculating machine, registering wheels, rotatable shafts, selecting elements 60 rotatably fast and longitudinally slideable upon said shafts, each element having circumferential teeth of graded lengths, a carrier for said shafts movable upwardly and downwardly, depressible keys adapted to turn said shafts axially, carrying mechanism including a rotary shaft bearing carrying members, means for moving said carrier upwardly and downwardly and said elements longitudinally to turn the registering wheels, and for rotating the carrying shaft including a rotary handle, and means co- 65 operating with said carrier for moving said shaft bodily toward and away from said wheels.
- 70 21. In a calculating machine, a shaft, a registering wheel thereon, a frame, a shaft mounted therein and arranged at right-angles to said first-named shaft, a selecting element thereon, means for moving said element endwise upon its shaft, and means for moving said frame to position said element in operative or inoperative relation to said registering wheel.
- 75 22. In a calculating machine, a shaft, a registering wheel thereon, a frame, a shaft mounted therein and arranged at right-angles to said first-named shaft, a selecting element thereon, reversible means for moving said element endwise in either direction upon its shaft, and means for moving said frame to position said element in operative or inoperative relation to said registering wheel.
- 80 23. In a calculating machine, a shaft, a registering wheel thereon, a frame, a shaft mounted therein and arranged at right-angles to said first-named shaft, a selecting element thereon, means for moving said element endwise upon its shaft, means for moving said frame to position said element in operative or inoperative relation to said registering wheel, a rocking shaft, an adjustable carrying member thereon, and means coöperating with said frame for rocking said last-named shaft.
- 85 24. In a calculating machine, a shaft, a registering wheel thereon, a frame, a shaft mounted therein and arranged at right-angles to said first-named shaft, a selecting element thereon having circumferential teeth of graded lengths, means for rotating said element, means for moving said element endwise upon its shaft, and means for moving said frame to position said element in operative or inoperative relation to said registering wheel.
- 90 25. In a calculating machine, a shaft, a registering wheel thereon, gears in connection with said wheel, a frame, a shaft mounted therein and arranged at right-angles to said first-named shaft, a selecting element thereon having circumferential teeth of graded lengths, means for rotating said element, means for moving said element endwise upon its shaft, and means for moving said frame to position said element in meshing relation with said gears.
- 95 100 105 110 115 120 125 130

26. In a calculating machine, registering wheels, gears in connection therewith, selecting elements having each a plurality of teeth of graded lengths movable transversely to 5 set up a selected number of the teeth of the elements and movable longitudinally in meshing relation with said gears.
27. In a calculating machine, registering wheels, gears in connection therewith, selecting elements each having a plurality of transverse teeth of graded lengths, depressible keys for moving the elements transversely in setting up, and means for moving the elements longitudinally in meshing 15 relation with said gears.
28. In a calculating machine, registering wheels, selecting elements having each a plurality of transverse teeth of graded lengths, depressible keys for moving said 20 elements transversely in setting up, and means for raising and lowering the elements and moving them longitudinally to actuate the registering wheels and reversely in a lower plane to normal position.
29. In a calculating machine, registering wheels, selecting elements having each a plurality of transverse teeth of graded lengths, means for moving the elements transversely in setting up, and means for raising and lowering the elements and moving them longitudinally in two directions to actuate the registering wheels in either direction of movement and reversely in a lower plane to normal position.
30. In a calculating machine, registering wheels, rotatable shafts, selecting elements rotatably fast and longitudinally slidable upon said shafts, each element having circumferential teeth of graded lengths, a carrier for said shafts movable upwardly and downwardly, means for turning said shafts axially in setting up, means adapted to raise and lower said carrier and to move said elements longitudinally to turn the registering 45 wheels, and dials indicating the numbers set up by the elements and having an operating connection with said shafts.
31. In a calculating machine, a transversely shiftable carriage bearing two series 50 of registering wheels, rotatable shafts, selecting elements rotatably fast and longitudinally slidable upon said shafts, each element having circumferential teeth of graded lengths, a carrier for said shafts movable upwardly and downwardly, means 55 adapted to turn said shafts axially, means for moving said carrier upwardly and downwardly and said elements longitudinally including a rotary handle, a cranked shaft and an arm engaging the cranked portion of said shaft, carrying mechanism relating to one of said series of registering wheels, and means for operating the other series of registering wheels having an actuating connection with said cranked shaft.
32. In a calculating machine, a transversely shiftable carriage bearing two series of registering wheels, rotatable shafts, selecting elements rotatably fast and longitudinally slidable upon said shafts, each 60 element having circumferential teeth of graded lengths, a carrier for said shafts movable upwardly and downwardly, means adapted to turn said shafts axially, means for moving said carrier upwardly and downwardly and said elements longitudinally including a rotary handle, a cranked shaft and an arm engaging the cranked portion of said shaft, carrying mechanism relating to one of said series of registering wheels, and means for operating the other series of registering wheels having an actuating connection with said cranked shaft.
33. In a calculating machine, a transversely shiftable carriage having a shaft and two series of registering wheels thereon, rotatable shafts, selecting elements rotatably fast and longitudinally slidable upon said shafts, each element having circumferential 75 teeth of graded lengths, a carrier for said shafts movable upwardly and downwardly, means adapted to turn said shafts axially, means for moving said carrier upwardly and downwardly and said elements longitudinally including a rotary handle, a cranked shaft and an arm engaging the cranked portion of said shaft, carrying mechanism relating to one of said series of registering wheels, and means for operating the other series of registering wheels having an actuating connection with said cranked shaft.
34. In a calculating machine, a transversely shiftable carriage having a shaft and two series of registering wheels thereon, rotatable shafts, selecting elements rotatably fast and longitudinally slidable upon said shafts, each element having circumferential 80 teeth of graded lengths, a carrier for said shafts movable upwardly and downwardly, means adapted to turn said shafts axially, means for moving said carrier upwardly and downwardly and said elements longitudinally including a rotary handle, a cranked shaft and an arm engaging the cranked portion of said shaft, carrying mechanism relating to one of said series of registering wheels, and means for operating the other series of registering wheels having an actuating connection with said cranked shaft.
35. In a calculating machine, a transversely shiftable carriage having a shaft and two series of registering wheels thereon, rotatable shafts, selecting elements rotatably fast and longitudinally slidable upon said shafts, each element having circumferential 85 teeth of graded lengths, a carrier for said shafts movable upwardly and downwardly, means adapted to turn said shafts axially, means for moving said carrier upwardly and downwardly and said elements longitudinally including a rotary handle, a cranked shaft and an arm engaging the cranked portion of said shaft, carrying mechanism relating to one of said series of registering wheels, and means for operating the other series of registering wheels having an actuating connection with said cranked shaft.
36. In a calculating machine, a transversely shiftable carriage having a shaft and two series of registering wheels thereon, rotatable shafts, selecting elements rotatably fast and longitudinally slidable upon said shafts, each element having circumferential 90 teeth of graded lengths, a carrier for said shafts movable upwardly and downwardly, means adapted to turn said shafts axially, means for moving said carrier upwardly and downwardly and said elements longitudinally including a rotary handle, a cranked shaft and an arm engaging the cranked portion of said shaft, carrying mechanism relating to one of said series of registering wheels, and means for operating the other series of registering wheels having an actuating connection with said cranked shaft.
37. In a calculating machine, a transversely shiftable carriage having a shaft and two series of registering wheels thereon, rotatable shafts, selecting elements rotatably fast and longitudinally slidable upon said shafts, each element having circumferential 95 teeth of graded lengths, a carrier for said shafts movable upwardly and downwardly, means adapted to turn said shafts axially, means for moving said carrier upwardly and downwardly and said elements longitudinally including a rotary handle, a cranked shaft and an arm engaging the cranked portion of said shaft, carrying mechanism relating to one of said series of registering wheels, and means for operating the other series of registering wheels having an actuating connection with said cranked shaft.
38. In a calculating machine, a transversely shiftable carriage having a shaft and two series of registering wheels thereon, rotatable shafts, selecting elements rotatably fast and longitudinally slidable upon said shafts, each element having circumferential 100 teeth of graded lengths, a carrier for said shafts movable upwardly and downwardly, means adapted to turn said shafts axially, means for moving said carrier upwardly and downwardly and said elements longitudinally including a rotary handle, a cranked shaft and an arm engaging the cranked portion of said shaft, carrying mechanism relating to one of said series of registering wheels, and means for operating the other series of registering wheels having an actuating connection with said cranked shaft.
- In testimony whereof I affix my signature in presence of two witnesses.
- EDGAR E. PHINNEY.
- Witnesses:
- L. D. DAGGART,
P. F. HARNETT.
